FRAME FOR MAKING FRINGE

Herman Milstein, Irving, Tex.
(18151 E. Valley Blvd., La Puente, Calif. 91744)

Filed May 17, 1973, Ser. No. 361,258

Term of patent 7 years

Int. Cl. D15—06

U.S. Cl. D92—15

FIG. 1

FIG. 2

FIG. 3

FIG. 4

FIG.
5

FIG.
6

FIG. 1 is a side perspective view of a frame for making fringe showing my new design;

FIG. 2 is a side elevational view, the other side being a mirror image thereof;

FIG. 3 is a top plan view;

FIG. 4 is a bottom plan view;

FIG. 5 is an end elevational view taken from the left of FIG. 2; and

FIG. 6 is an elevational view of the other end.

I claim:

The ornamental design for a frame for making fringe, substantially as shown and described.
